PACKAGE FILLING MACHINE

William E. Higginbottom, Newark, N. J., assignor
to Benjamin C. Betner Company, Devon, Pa.,
a corporation of Delaware

Application December 15, 1944, Serial No. 568,307

10 Claims. (Cl. 226—125)

1

It is the primary object of this invention to provide a package filling machine of the auger type which will deliver either automatically, or at the will of the operator, a charge of pulverulent material of predetermined volume.

It is a further object of this invention to provide a machine of the class aforesaid which will so closely control the consistency of the bulk charge delivered as to provide not only accurate volume, but also accurate weight.

It is a further object of this invention to provide a machine of the class described in which all parts driving the auger are mounted above the level of discharge of the spout.

It is a further object of this invention to provide a machine of the class aforesaid which is compact, simple, and in which all bearings are shielded from contamination by the material being packaged.

It is a further object of this invention to provide a machine of the class aforesaid in which the auger, its driving mechanism and all associated parts are simply and easily vertically adjustable toward and away from the level of the table supporting the packages to be filled.

It is a further object of this invention to provide a machine of the class aforesaid in which the hopper may easily be removed and cleaned and in which the removal of the hopper facilitates cleaning of the auger and associated parts.

The above and other objects will be made clear from the following detailed description, taken in connection with the annexed drawings, in which:

Figure 1 is a side elevation showing the general organization and mounting of the machine;

Fig. 2 is a front elevation of the parts shown in Fig. 1;

Fig. 3 is a section on the line 3—3 of Fig. 1;

Fig. 4 is a section on the line 4—4 of Fig. 5;

Fig. 5 is a section on the line 5—5 of Fig. 4;

Fig. 6 is a section on the line 6—6 of Fig. 4;

Fig. 7 is a section on the line 7—7 of Fig. 4; and

Fig. 8 is a view, partly in section, of the auger and agitator extending downwardly from the mechanism illustrated in Fig. 5.

The auger type of packer performs two distinct functions. The first is positive feeding of the material. The second is delivery of a controlled quantity of material. Mathematically, the nature of this type filler is such that controlled volume is naturally within its capacity. If, in addition, the consistency or density of the material is also controlled, then the weight of material delivered is equally controlled. It is important to note that in all commercial pack-

aging operations there is no such thing as absolute control. Even the most accurate scales deliver either over or under, and, regardless of the method of measurement, it is always standard practice to adjust the measuring machine to deliver somewhat more than the labeled contents in order to avoid substandard deliveries. This overage, of course, is costly, and the greater the accuracy of the filling machine, the less overage is required.

Considered as a matter of percentage, accuracy decreases with the unit quantity being measured. This is true irrespective of the nature of the measuring means. It is also true that, as the quantity decreases, the efficiency of automatic scales, or any bulk determiner of the "container" type, in which a receptacle is filled and then dumped into a package, also decreases. The primary reason for this is that, while twenty packages per minute is a tremendous rate when the unit is one hundred pounds, forty per minute is extremely slow when the unit is only one or two ounces. The time factor works strongly against the filling of any type container with a controlled charge. For example, three automatic scales

20 are ample to pace twenty one-hundred pound units per minute, while six automatic scales have trouble pacing forty two-pound units per minute, although handling only 4 per cent of the quantity.

25 The auger packer is perfectly controllable volumetrically. It has a fixed pitch. It may fit the spout closely, and it, therefore, delivers an almost perfectly fixed volume of material per revolution. The number of revolutions may be

30 closely controlled, and the volume delivered per cycle of operations may be equally controlled. If, then, the density of the material passing through the convolutions of the auger may be

35 stabilized, the weight is subject to the same control. The auger is positive and fast, particularly for small quantities, and, when such quantities are involved, a single auger will do the work of several scales, with equal accuracy.

40 In plants packaging pulverulent material, the machines usually must work in a dusty atmosphere. Moreover, in the course of filling millions of packages, there must, inevitably, be leakage and spillage of the material upon the surface over which the packages pass for the filling operation. When, as in this case, the parts must work rapidly and accurately, contamination of the parts by the material being packaged has a very serious effect upon the efficiency of the machine.

45 The present invention, therefore, is in large part

directed to organizing the parts, and mounting them so as to be completely sealed against the ingress of dusty atmosphere, and completely out of the way of material which may be spilled during the filling operation.

In many packaging plants relatively small quantities in a wide variety of materials are put up in the course of a week or even in the course of one or two days. This situation is apt to occur for example, in the packaging of spices or drugs. In such plants it is impracticable to operate a separate machine for each commodity to be packaged, yet when a single machine is used, it is necessary to clean all of the parts over which the material passes whenever the machine is changed from the handling of one commodity to the handling of another. The machine disclosed herein is particularly adapted to facilitate such cleaning operations.

Referring now to Figs. 1, 2 and 3, there is shown a table 10 over which pass the packages 12 to be filled. The table 10 is supported by legs 14. Above the table 10 is a delivery spout 16 in which an auger 18 rotates. A hopper 20 is above and connected with the spout 16 and receives pulverulent material through a chute 22 from a supply bin (not shown). Standards 26 are mounted adjustably in the legs 14 and in turn support a housing 30 containing the driving means for the auger 18. It is to be noted that the housing 30 lies wholly above the delivery level of spout 16.

A screw lift 21 is connected by a bar 23 with the legs 26 and is operative to adjust the vertical position of the spout 16, the hopper 20 and the drive mechanism 30 toward and from the table 10 to accommodate various heights of packages 12.

Referring now to Figs. 1 and 5, there is shown a motor 32 the shaft 34 of which enters the housing 30 through a bearing 36. The lower end 38 of the shaft 34 is restrained laterally by a sleeve 40 in a bushing 42. A pinion 44 is mounted on the shaft 34 and is supported on a thrust bearing 46.

The pinion 44 drives a gear 48 mounted to rotate freely about a shaft 50 and also drives a gear 52 mounted on a stub shaft 54. A pinion 56 is also mounted on the stub shaft 54 and is secured to the gear 52 and is driven thereby.

The pinion 56 meshes with a gear 58 keyed to a shaft 60 (Fig. 7). The shaft 60 passes through the housing 30 and has keyed to its lower end a pulley 62.

The shaft 50 about which the gear 48 freely rotates, also penetrates the housing 30 and has keyed to its lower end a pulley 64 (Fig. 5).

A belt 66 connects the pulley 62 with the pulley 64 and the shaft 50 is thereby driven from the motor 32 via pinion 44, gear 52, pinion 56, gear 58, pulley 62, belt 66 and pulley 64.

On the underside of the housing 30 and concentric with the shaft 60 is mounted a bracket 70 having a projecting arm 72 at the end of which is a stub shaft 74 on which is rotatably mounted a flat faced pulley 76. On the side of the bracket 70 substantially opposite the arm 72 is a worm gear segment 78. The segment 78 meshes with a worm 80 mounted on a shaft 82. The shaft 82 is supported in bearings 84 attached to the underside of the housing 30 and has as its free end a hand-crank 86.

The flat faced pulley 76 is adapted to bear against the belt 66 and its pressure against the belt may be adjusted by means of the hand crank 86, the worm 80, the segment 78 and the arm 72. The belt 66 is V-shaped in cross section and bears in similarly shaped grooves in the pulleys 62 and

64. The effect is that of a reeves drive and provides a means for making moderate adjustments of the ratio between pulleys 62 and 64.

The gear 48 meshes with another gear 90 which rotates freely about a bushing 92 on a shaft 94. The gear 90 is keyed at 96 to a clutch member 98.

A complementary clutch member 100 is slidably keyed to the shaft 94. The clutch member 100 has a central groove 102 which receives the stubs 104 of a yoke 106 which forms one arm of a bell crank. The other arm 108 terminates in an anti-friction bearing 110 supporting a sleeve 112. The apex of the bell crank is a boss 114 surrounding a stub shaft 116 supported by the housing 30.

A spring 120 tends to lift the yoke 106 and thereby to lift the clutch member 100 away from engagement with the clutch member 98.

The function of the shaft 50 will now be described. This shaft is guided at its lower end by a bearing 130 and adjacent its upper end by a bearing 140. One member 142 of a one revolution clutch is keyed to the shaft 50. The other member 144 freely surrounds the shaft 50 and acts as a bushing between it and the bearing 140. The clutch member 144 has secured to its upper end a cam 146 against which the sleeve 112 of the arm 108 is pressed by the action of the spring 120. As the cam 146 revolves, its active surface tilts the bell crank to bring the clutch member 100 into active engagement with the clutch member 98 which is driven by the gear 90. This engagement rotates the shaft 94 to which the auger 18 is attached through a chuck 150 (see Fig. 8). This active surface of the cam 146 is formed of two overlapping segments 146' and 146'', the amount of overlap being adjustable by turning segment 146'' about the axis of shaft 50 when the adjustment screw 147 is loosened. An opening is provided in the housing 30 to give access to the cam 146 and is closed by a removable cover plate 152.

Keyed to the shaft 94 is a pinion 160 which meshes with a gear 162 mounted on a stub shaft 164 (Fig. 6). A pinion 166 is also mounted on the stub shaft 164 and is secured to the gear 162 to rotate therewith. The pinion 166 meshes with a gear 168 which is keyed to a sleeve 170. The sleeve 170 surrounds the shaft 94 and is spaced therefrom by a bushing 172. A collar 174 (Fig. 8) is secured to the lower end of the sleeve 170 and agitating members 176 and 176' are secured to the collar 174. The lower end of the sleeve 170 is spaced from the shaft 94 by a bushing 178 and its extremity is hollowed out to receive an oil-tight bushing 180 which surrounds the shaft 94.

A supplementary sleeve 200 (Figs. 5 and 8) is bolted to the casing 30. This guides the upper end of sleeve 170 by means of a bushing 201 (Fig. 5) and guides the lower end of sleeve 170 by means of a bushing 202 (Fig. 8). The open end of sleeve 200 is sealed by means of an oil-tight bushing 203 (Fig. 8).

Whenever the clutch members 98 and 100 are engaged the agitators 176' are rotated around the chuck 150 but at a speed considerably less than that of the auger. These agitators not only insure the availability of material for delivery to the auger but preserve uniformity in the consistency of the material delivered.

If the agitators were not present material descending to the hopper 20 from the chute 22 would tend to cake and therefore either would not reach the auger 18 at all or would reach it with varying consistency which would destroy the

desired constant relationship between weight and volume. The agitator 176 is nearer to the axis of shaft 94 than is the agitator 176'. These two members therefore describe concentric circles about the shaft 94 and insure the delivery of material of uniform consistency to the auger 18.

When the clutch member 100 is drawn upwardly by the spring 120, its upper surface 100' engages a friction brake which prevents continued free rotation of the shaft 94. Inasmuch as there is frequent and sharp engagement of the surface 100' with the friction brake and inasmuch as the parts are wholly enclosed, there is considerable generation of heat. For this reason an anti-friction bearing 180 having both radial and axial resistance is affixed to the upper end of the shaft 94 and a compression spring 182 bears thereon. Any elongation of the shaft 94 under the effect of heat is therefore absorbed through compression of the spring 182.

It is to be noted that the speed of rotation of the shaft 94 is determined directly by the speed of the motor 32. The duration of each cycle of its operation, however, is capable of very considerable adjustment through the adjustability of the cam 146 and of minor adjustment by means of pulley 16. The one-revolution clutch members 142 and 144 are controlled by a latch 141 operated by linkage 143, controlled by foot pedal 143' (Fig. 1). When a container 12 has been placed under the spout 16, the linkage 143 is operated to withdraw the latch 141. The consequent rotation of the cam 146 engages clutch members 98 and 100 causing rotation of the shaft 94 and of the agitators so long as such engagement persists. When the end of the cam surface is reached, spring 120 disengages the clutch members and brakes shaft 94. Shortly thereafter the one revolution clutch re-engages the latch 141 and stops the continued rotation of cam 146.

It is, therefore, evident that the instant invention provides a package filling machine in which there is complete and adjustable control of the volume delivered at each operation; such control of the consistency of the material delivered that control of volume becomes synonymous with control of weight; and in which all operating parts are located above the level of discharge of the filling spout and are therefore free of contamination due to leakage and spillage. The parts are, moreover, so compactly arranged as to be sheltered within a single housing, fully sealed from the outer atmosphere.

In order to permit cleaning of the hopper 20 and of the rotating parts extending therethrough, the hopper 20 is suspended by means of bolts 200 passing through brackets 202 mounted on the hopper 20, the bolts being pivoted to a flange 204 on a split housing 206 which encloses the drive mechanism casing 30. The bolts 200 may readily swing to disengage from the pivots 202 to permit the hopper 20 to be withdrawn for cleaning purposes, a step which exposes all of the rotating mechanism connected with the auger 18 to facilitate the cleaning of such parts. A door 210 is provided in the front of the hopper 20 to give access to the interior of the hopper for correcting any minor operating difficulties.

The agitators 176 will tend to pile up a quantity of pulverulent material entering the hopper through the chute 22 to a level above the level of the agitators. In order further to perfect the control of the density of the material delivered to the auger, a lip 219 is provided which directs the

material entering through the chute 22 so as to fall clear of a spillway 220 which is provided in the hopper 20. The spillway 220 limits the level to which material may be built up by the agitators. Such a spillway may be provided with an adjustable lip 222 for close adjustment of the level of material and communicates with any suitable form of conveyor 224 to return material passing through the spillway back to the original source of supply.

I claim:

1. In a package filling machine, a spout, an auger therein, a shaft connected to said auger, a pair of clutch members concentric with the axis of said shaft, one of said members being keyed to said shaft, a cam for engaging said clutch members, said cam being mounted freely on a shaft parallel to the axis of said auger shaft, a gear freely rotatable about said cam bearing shaft and driving one of said clutch members, a one-revolution clutch for driving said cam from said cam bearing shaft, a motor for driving all of said parts, said motor being geared to said freely rotatable gear, and driving said cam bearing shaft through a reeves drive.
2. In a package filling machine, a spout, an auger therein, a shaft connected to said auger, an agitator rotatable about said shaft, a counter-shaft parallel to said auger shaft and carrying reduction gearing to drive said agitator from said auger shaft, a pair of clutch members concentric with said auger shaft, one of said members being freely rotatable about said auger shaft, and the other being keyed thereto, a single, constantly running motor for driving all of the parts, said motor being geared directly to said freely rotatable clutch member, and a one-revolution clutch mechanism arranged to actuate the other of said clutch members whereby to rotate said auger shaft and consequently said agitator.
3. In a package filling machine, a spout, an auger therein, a shaft connected to said auger, a pair of clutch members concentric with the axis of said shaft, one of said members being keyed to said shaft, a cam for engaging said clutch members, said cam being mounted freely on a shaft parallel to the axis of said auger shaft, a gear freely rotatable about said cam bearing shaft and driving one of said clutch members, a one-revolution clutch for driving said cam from said cam bearing shaft, a motor for driving all of said parts, said motor being geared to said freely rotatable gear, and driving said cam bearing shaft through a reeves drive; and means for adjusting the portion of each rotation of said one-revolution clutch during which said pair of clutch members are engaged.
4. In a package filling machine, a spout, an auger therein, a shaft connected to said auger, an agitator rotatable about said shaft, a counter-shaft parallel to said auger shaft and carrying reduction gearing to drive said agitator from said auger shaft, a pair of clutch members concentric with said auger shaft, one of said members being freely rotatable about said auger shaft, and the other being keyed thereto, a single, constantly running motor for driving all the parts, said motor being geared directly to said freely rotatable clutch member, and a one-revolution clutch mechanism arranged to actuate the other of said clutch members whereby to rotate said auger shaft and consequently said agitator, and means for adjusting the portion of each rotation of said one-revolution clutch mechanism during which said pair of clutch members are engaged.

5. A machine for delivering pulverulent material, comprising a spout, an auger within said spout, a shaft connected to and coaxial with said auger, a constantly driven auxiliary shaft parallel to said auger shaft, each of said shafts having a pair of clutch members concentric therewith, one member of each pair being secured to its respective shaft, constantly driven means concentric with said auxiliary shaft for driving the free clutch member of the auger shaft, means connected with the free clutch member of said auxiliary shaft for engaging the clutch members of said auger shaft, and means operable to engage the clutch members of said auxiliary shaft and to disengage the same after a predetermined period of engagement.

6. A machine for delivering pulverulent material, comprising a spout, an auger within said spout, a shaft connected to and coaxial with said auger, a constantly driven auxiliary shaft parallel to said auger shaft, each of said shafts having a pair of clutch members concentric therewith, one member of each pair being secured to its respective shaft, constantly driven means concentric with said auxiliary shaft for driving the free clutch member of the auger shaft, means connected with the free clutch member on said auxiliary shaft for engaging the clutch members of said auger shaft, and means operable to engage the clutch members of said auxiliary shaft and to disengage the same after a predetermined period of engagement, said means for engaging the clutch members of said auger shaft being adjustable to determine the period of engagement of said clutch members within the period of engagement of said auxiliary shaft clutch members.

7. A package filling machine comprising a spout, a rotatable auger within said spout, a hopper connected with and mounted above said spout, an agitator in said hopper mounted to rotate about the axis of said auger, said agitator acting to pile material in said hopper above the level of said agitator, and a spillway in said hopper, said spillway having a lip above the level of said agitator, whereby to limit the level of material in said hopper above said agitator.

8. In a package filling machine, a spout, an auger therein, an agitator connected with said auger, a hopper surrounding said agitator, an inlet to said hopper for material to be packed, a

spillway connected to said hopper above the level of said agitator, and an adjustable lip on said spillway, whereby the level of material in said hopper may be closely controlled.

5 9. In a package filling machine, a spout, an auger therein, a hopper connected to said spout, an inlet to said hopper for material to be packed, a spillway connected to said hopper, and an adjustable lip on said spillway, whereby the level of material in said hopper may be closely controlled.

10 10. A package filling machine for delivering predetermined quantities of pulverulent material, comprising a table for supporting packages to be filled, supports extending upwardly from said table and supporting thereabove a mechanism housing, a hopper for pulverulent material detachably secured to said housing and terminating at its lower end in a material delivery spout, a 15 combined auger feed and material agitator shaft assembly supported from said housing and passing vertically through said hopper, a feeding auger on the lower end of said shaft assembly lying within said material delivery spout, at least 20 one material agitator connected to said shaft assembly and lying within said hopper, a prime mover and drive mechanism located within said housing, connections between said drive mechanism and the upper end of said shaft assembly 25 for driving the latter from the former for a predetermined number of revolutions, and means for 30 adjusting said drive mechanism to alter the number of such revolutions.
